(57) **CLAIM**

The ornamental design for a combined cooking machine with pot, as shown and described.

DESCRIPTION

FIG. 1 is a front perspective view of a combined cooking machine with pot, showing my new design;
 FIG. 2 is a rear perspective view thereof;
 FIG. 3 is a front elevational view thereof;
 FIG. 4 is a rear elevational view thereof;
 FIG. 5 is a left side elevational view thereof;
 FIG. 6 is a right side elevational view thereof;
 FIG. 7 is a top plan view thereof; and,
 FIG. 8 is a bottom plan view thereof.

The broken lines in the drawings depict portions of the combined cooking machine with pot form no part of the claimed design.

1 Claim, 8 Drawing Sheets
